CHECK-PROTECTING MEANS

Raymond E. Bauder, Chicago, Ill.

Application April 2, 1937, Serial No. 134,653

8 Claims. (Cl. 283—58)

The invention relates to check protecting means of the general type in which the check is provided with an amount-indicating area to be torn away according to the amount of the check, and in which a tearing strip is provided under which to insert a desired portion of said area, the strip constituting a guide for use in tearing said portion from the check, leaving the remaining portion of the amount-indicating area attached to the check. I am aware that devices of this general type have heretofore been provided, but the present invention aims to provide a new and improved means for attaining the desired end.

One of the foremost objects of the invention is to provide a novel construction in which the tearing strip is secured to the bound stack of checks and stubs and permanently located upon the uppermost stub at the bound end thereof, in position for use whenever required.

A further object is to secure the tearing strip to the check-book by the same binding means which secures the stubs.

Another object is to make novel provision for limiting the insertion of the check under the tearing strip.

Yet another object is to make novel provision to facilitate ejection of the torn off check portion from beneath the tearing strip.

A still further object is to provide novel means to prevent slipping of the check while tearing the desired portion thereof.

Yet another object is to provide exceptionally simple and inexpensive, yet convenient and desirable means for attaining the required results.

With the foregoing in view, the invention resides in the novel subject matter hereinafter described and claimed, description being accomplished by reference to the accompanying drawing.

Fig. 1 is a top plan view showing a check-book provided with the check-protecting means, the front cover being removed.

Fig. 2 is an enlarged edge view partly in longitudinal section showing the amount-indicating portion of a check inserted under the tearing strip.

Fig. 3 is a view similar to Fig. 2 but showing the check-book and the tearing strip in readiness for tearing the desired portion of the amount-indicating area from the check.

Fig. 4 is a perspective view of the tearing strip.

The construction shown in the drawing may be considered as preferred and will be rather specifically described, with the understanding, however,

that variations may be made within the scope of the invention as claimed.

A check-book 10 is shown having the usual bound stack of checks 11 and stubs 12 integrally joined to each other and having a perforated line of juncture 13 to facilitate tearing of any check from its stub. The stubs 12 are bound together by staples or the like 14 and these staples may also secure the front and back covers 15 and 16 of the book.

Immediately to the right of the tear line 13, I provide each check 11 with an amount-indicating area 17 preferably consisting of a column of numbers printed on the check adjacent the perforated line 13. A tearing strip 18 of metal, Celluloid, or other suitable material is provided, under which to insert a desired portion of the area 17 of any check after detaching said check from its stub, for holding said portion while severing it from the check, said tearing strip 18 being provided with a relatively long longitudinal edge portion 19, with an oblique edge portion 19a extending inwardly from one end of said edge portion 19, and with a relatively short edge portion 19b at the inner end of said portion 19a. The edge portions 19 and 19a are preferably turned laterally and sharpened as shown, or serrated if desired, and they serve to hold the check to be severed when pushed against the same, and to sever the desired portion of the area 17 from said check when the latter is pulled upwardly and toward the user.

The tearing strip 18 is secured to the bound stack and is permanently located upon the left end of the uppermost stub, the binding means 14 being preferably used in securing said tearing strip, although other attaching means could, of course, be employed if desired. This tearing strip 18 is provided with a plurality of downwardly stamped stops 20 to limit the insertion of the check under said tearing strip as seen in Fig. 2, and said tearing strip is also preferably provided with a plurality of transverse slots 21 or with other openings through which air may be blown from the user's mouth to facilitate removal of a previously torn off check portion from beneath said tearing strip. The stops 20 are so located as to prevent insertion of the check under the edge portion 19b of the strip 18, as such insertion would interfere with proper movement of the check when tearing.

When the check-book and the tearing strip 18 are being secured together, the pressure applied by the stapling, binding, or paper cutting machine forces said tearing strip 18 somewhat into

the uppermost stub 12 providing a shallow recess 22 in said stub, in which recess said strip 18 is seated. The downturned edge portions 19 and 19^a depress the underlying portions of the aforementioned stub and a number of the subjacent stubs, forming grooves in which said down-turned edge portions are normally received, one of said grooves being shown at 23. Similarly, the stops 20 form sockets 24 in which they are received.

10 When the check and the tearing strip 18 are relatively angled as seen in Fig. 2 to provide an intervening space 25 into which to insert the area 17 of a torn-off check, the stops 20 do not entirely leave the sockets 24 and it is thus insured when inserting a check, that said check cannot pass under said stops and enter too far. When this relative angling of checks and tearing strip 18 occurs, however, the down-turned edge portions 19 and 19^a entirely leave the grooves 23 and cannot interfere with insertion of the check. When the checks and the tearing strip 18 are restored into substantially parallel relation with each other and said strip 18 is pressed downwardly upon the inserted end of the check, the edge portions 19 and 19^a slightly force the check into the grooves 23, effectively holding said inserted end of the check against slipping while pulling the check upwardly and toward the user to sever said inserted end from the check.

30 To facilitate the relative angling of the checks and the strip 18, the back cover 16 of the book is preferably provided with a hinge line 26 under said strip 18. By grasping the bound end of the book and thereby supporting said book in a more or less horizontal position, the cover 16 and the checks have a tendency to fall away from the strip 18 to form the space 25 for check reception. Also after the undesired portion of any check has been severed from that check, the hinge line 26 permits more easy release and removal of the torn-off portion. In most cases, by simply holding the check-book by its bound end and lightly shaking it, the torn-off portion will fall out, but if it should fail to do so, the user may loosen it by blowing air from his mouth through the openings 21. These openings may well extend inwardly to such an extent that the user may insert a pin or the like through any of them and thereby push against the inner edge of the torn-off check portion, to remove it in this way if desired.

50 For the average check-book, one column of amount-indicating numbers on the area 17, will suffice. However, for larger amounts, two or more columns could of course be employed, one column or another being completely torn off if necessary before so tearing as to indicate the amount of the check.

It will be seen from the foregoing that novel provision has been made for carrying out the objects of the invention, and while the details disclosed are preferably followed, attention is again invited to the possibility of making variations within the scope of the invention as claimed.

65 While I have herein referred to the strip 18 as a "tearing strip", its sharp edges 19 and 19^a of course cut the check to a large extent when sufficiently sharpened or serrated.

I claim:

1. A check-book having a bound stack of checks and stubs, the left ends of the checks being joined to the right ends of the stubs along weakened tear lines to allow any check to be detached from its stub in the usual way, each check being provided with a printed indicating portion to the right of its tear line to be torn away according to the amount of the check after detaching the check from its stub, and an elongated tearing strip secured to said stack and permanently located upon the uppermost stub for use as a guide when tearing said indicating portion of any detached check, said tearing strip having a free right edge under which to insert said indicating portion. 5

10 2. A structure as specified in claim 1; said tearing strip being secured to said stack by the same means which binds said stack.

15 3. A structure as specified in claim 1; said tearing strip being provided with a downwardly projecting stop to limit the insertion of the check thereunder.

20 4. A structure as specified in claim 1; said tearing strip being provided with an opening through which the user may blow air from his mouth to loosen and facilitate removal of a previously torn off check portion.

25 5. A structure as specified in claim 1; said tearing strip being provided with a downwardly projecting stop to limit insertion of the check under said strip, said uppermost of the stubs having a socket receiving said stop to prevent the check from passing under said stop when inserting it.

30 6. A structure as specified in claim 1; said tearing strip having a free downturned cutting edge under which to insert said indicating portion, said uppermost of the stubs being provided with a groove into which said cutting edge forces the check when using the device, preventing 40 slippage. 35

45 7. A structure as specified in claim 1; said tearing strip being provided with an opening through which the user may blow air from his mouth to loosen and facilitate removal of a previously torn off check portion, said opening being so positioned as to give access to the inner edge of the torn off check portion if it be desired to push it out with the aid of a pin or the like. 50

55 8. A check-book having a stack of checks and stubs and a back cover bound together, the left ends of the checks being joined to the right ends of the stubs along weakened tear lines to allow any check to be detached from its stub in the usual way, each check being provided with a printed indicating portion to the right of its tear line to be torn away according to the amount of the check after detaching the check from its stub, and an elongated tearing strip secured to 60 said stack and permanently located upon the uppermost stub for use as a guide when tearing said indicating portion of any detached check, said tearing strip having a free right edge under which to insert said indicating portion, said back 65 cover having a hinge line under said tearing strip for the purpose set forth.

RAYMOND E. BAUDER.
